GEORGE FUSSELL, OF CHICAGO, ILLINOIS.

NON-REFILLABLE-BOTTLE CLOSURE.

1,106,505.

Specification of Letters Patent. Patented Aug. 11, 1914.

Application filed September 18, 1913. Serial No. 790,491.

To all whom it may concern:

Be it known that I, GEORGE FUSSELL, a citizen of the United States, residing at Chicago, in the county of Cook and State of Illinois, have invented certain new and useful Improvements in Non-Refillable-Bottle Closures, of which the following is a specification.

This invention relates to a non-refillable bottle closure wherein a hollow stopper containing the necessary check valve and obstruction preventing interference therewith is inserted within a bottle neck having a lateral pouring aperture communicating with the space in the stopper above the valve and having also an inserted non-removable plug securing the stopper in position.

The invention also comprises a provision to prevent the bottle being filled by inverting it in a vessel of the liquid which it is required to hold.

The invention is particularly described in the following specification, reference being made to the drawings by which it is accompanied, in which:

Figure 1 being a vertical section of the bottle neck having the non-refillable closure complete, and Fig. 2 is a cross section of the bottle neck and stopper through the pouring aperture. Fig. 3 is a detailed cross section on the line 3—3 of Fig. 1.

In these drawings 2 represents the neck of the bottle, the bore of which is accurately molded or is ground with a slight taper as far as is necessary to form a seat for the stopper and in the upper part of the neck is a lateral pouring aperture 3.

Seated within the lower part of the bottle neck and extending a short distance above the lateral pouring aperture 3 is a hollow stopper 5 which has a sealing ring 10 of cork or other suitable material fitting a shouldered recess provided for it in the lower end.

The full diameter of the bore of this stopper 5 is open to the upper end, and at the lower end there is an aperture 7 which is axial with the bore and of smaller diameter. A buoyant hollow valve 8 loosely fits the bore of this stopper, which valve has a hemispherical lower end which seats over the aperture 7. To the lower end of this valve 8 a weight 13 is suspended by a fine wire or filament 6, which weight is also connected by a similar filament to a spur 18 projecting downward from the underside of the stopper 5 and bent into axial alinement with the

valve 8. This filament connection between the weight 13 and spur 18 is of such length as will allow the valve to move off its seat a sufficient amount only to provide passage 60 through the aperture 7.

In the side of the bore 19 of the stopper which is toward the pouring aperture 3 of the bottle, two vertical flutes or grooves 15 are formed in the bore and extend from the upper edge as far as the seat of the valve. To enable these flutes to be formed in the thickness of the wall of the stopper the axis of the bore of it is eccentric with the outside of the stopper. Toward the upper end of the stopper, each flute 15 connects with a passage 16 on each side delivering to the outside of the stopper, which passages connect there with a passage 17 which is carried around the outside of the stopper and connects the inner bore of it with the pouring aperture 3 of the bottle neck. This stopper 5 with its valve 8 is inserted in the neck of the bottle and seats therein with the upper edge of it just above the lateral pouring aperture 3 and over it in the neck of the bottle is inserted a locking plug 20 which is provided with a sealing ring 21 of cork or similar material around its lower end and with a circumferential groove 23 which registers with a similar circumferential groove in the neck of the bottle and into these grooves small balls 24 are passed from magazine ducts within the stopper. This locking stopper being the subject of a separate application need not be further enlarged upon. It is designed to be non-removable after it has once been inserted.

In use, the bottle being filled in the usual manner, its stopper 5 and locking plug 20 are inserted and the pouring aperture 3 is closed with a small cork and may be sealed. When this cork is removed from 3 and the bottle is tilted, as in the act of pouring, the liquid acting on the underside of the valve 8 will lift that valve and will flow through the aperture 7 and along the grooves 15, and through the opposed ducts 16 and passage 17 to the pouring aperture 3. On turning the bottle to its vertical position the valve 8 will close the aperture 7 by its own weight and that of the weight 13 connected to it. The bottle cannot be refilled through the closure stopper as the locked plug 20 cannot be removed to give access to the valve 8 and that valve cannot be interfered with through the aperture 3.

owing to the obstruction that the wall of the plug offers to direct access therethrough and any liquid poured inward through the aperture 3 can not pass the valve 8. If the bottle is inverted and immersed in a liquid the buoyancy of the hollow valve 8 will hold it against its seat and prevent ingress and if it is laid on its side the weight 13 will hang on its filaments, as indicated by the 10 dot and dash lines in Fig. 1, and hold the valve 8 to its seat unless, as in pouring, there is a fluid pressure within the bottle.

The bottle stopper and its several correlated parts may be made of any suitable 15 material that will be non-corrosive under the action of the liquid the bottle is designed to hold.

Having now particularly described my invention, I hereby declare that what I 20 claim as new and desire to be protected in by Letters Patent, is:

1. In a non-refillable bottle, a bottle neck 25 having a lateral pouring aperture, a hollow stopper secured within the neck of the bottle the upper edge of the stopper extending above the bottom of the lateral pouring aperture said stopper having an aperture in the bottom end and a passage in the upper part connecting the cavity of the stopper indirectly with the pouring aperture of the bottle, and a buoyant valve seated within the stopper over the bottom aperture.

2. In a non-refillable bottle, a bottle neck 35 having a lateral pouring aperture, a hollow stopper secured within the neck of the bottle the upper edge of the stopper extending above the bottom of the lateral pouring aperture said stopper having an aperture in the bottom end and a passage in the upper part connecting the cavity of the stopper indirectly with the pouring aperture of the bottle, a buoyant valve seated within the stopper over the bottom aperture means for 40 limiting the upward movement of this valve, and means for holding the valve on its seat when the bottle is inclined from the vertical and the fluid pressure without is greater than that within the bottle.

3. In a non-refillable bottle, a bottle neck 50 having a lateral pouring aperture, a hollow stopper secured within the neck of the bottle the upper edge of the stopper extending above the bottom of the lateral pouring aperture said stopper having an aperture in the bottom end and a passage in the upper part connecting the cavity of the stopper indirectly with the pouring aperture of the bottle, a buoyant valve seated within the 55 stopper over the bottom aperture, a flexible connection from the underside of the valve to an attachment projecting downward from the underside of the stopper and a weight about the midlength of said connection.

4. In a non-refillable bottle, a bottle neck having a lateral pouring aperture, a hollow stopper secured within the neck of the bottle the upper edge of the stopper extending above the bottom of the lateral pouring 70 aperture said stopper having an aperture in the bottom end and a passage in the upper part connecting the cavity of the stopper indirectly with the pouring aperture of the bottle, said stopper having also a spur downwardly projecting from its underside, a buoyant valve over the aperture in the bottom of the stopper, a weight suspended by a flexible connection to the underside of the valve, said weight connected also by a 75 flexible connection to the downwardly projecting spur of the stopper.

5. In a non-refillable bottle, a bottle neck having a lateral pouring aperture, a hollow stopper seated within the neck of the bottle 85 the upper end of the stopper extending above the bottom of the lateral pouring aperture said stopper having an aperture in the bottom end and an indirect passage from the inside of it communicating with the 90 pouring aperture, and a projection extending downward from its lower end, a buoyant valve seated over the bottom aperture of the stopper, a flexible connection between the valve and the downward projection 95 from the stopper, a weight in the midlength of that connection, and means for retaining the stopper within the bottle neck.

6. In a non-refillable bottle, a bottle neck having a lateral pouring aperture, a hollow 100 stopper seated within the neck of the bottle the upper end of the stopper extending above the bottom of the lateral pouring aperture in the bottle neck the bore of said stopper having an aperture in the bottom, 105 a projection extending downward from its lower end and an indirect passage from the upper end of the bore communicating with the pouring aperture, a buoyant valve seated over the aperture in the lower end of 110 the stopper and connected by a filament or the like to the downward projection of the stopper, said connection having a weight about its midlength, means for sealing the hollow stopper within the neck of the bottle, 115 and means for permanently closing the upper end of the bottle neck over the stopper.

7. In a non-refillable bottle, a bottle neck having a lateral pouring aperture, a hollow stopper seated within the neck of the bottle 120 the upper end of the stopper extending above the bottom of the lateral pouring aperture in the bottle neck, the bore of said stopper being eccentric with its external surface from the lateral pouring aperture and having on the thicker side of its inside wall 125 vertical grooves or flutes extending from a contracted opening in the bottom of it to the upper end, passages connecting the bore of the stopper with a passage around the 130

upper end of the stopper communicating with the pouring aperture, a buoyant valve loosely fitting the bore of the stopper and seating on the opening in the lower end of 5 it said valve connected by a filament or other flexible connection to a downward projection from the lower end of the stopper and a weight secured to that connection about its midlength, means for sealing the 10 stopper within the neck of the bottle, a locking plug secured in the upper end of the bottle neck, and means for sealing that plug in the neck of the bottle.

8. In a non-refillable bottle, a bottle neck 15 having a mouth and a lateral pouring aperture, a hollow stopper fitted into said neck below the lateral pouring aperture, and including a portion extending above the bottom of the lateral pouring aperture, said 20 hollow stopper having a chamber extending from its upper end toward its lower end and restricted at its lower end to form a valve seat, said stopper having a peripheral groove registering with said lateral pouring 25 aperture and having an aperture to form communication between said groove and the interior of the stopper chamber, a valve mounted in said stopper chamber to engage said seat, means continuously tending to 30 hold said valve on its seat and a locking plug inserted in the bottle neck above said stopper to close the upper end of the stopper chamber and close the bottle neck mouth substantially as shown and described.

35 9. As a bottle closure for bottles having

a mouth and a lateral pouring aperture, a stopper adapted to be inserted in the bottle neck and extend below the lateral pouring aperture, said stopper having a chamber extending from its upper end toward its 40 lower end and terminating at its lower end in a restricted valve seat portion, a buoyant valve mounted in said stopper chamber, and conforming closely to the same, said stopper having longitudinal flutes for conducting 45 the liquid by said valve when said valve is unseated, a plug for closing the bottle neck mouth and also closing the stopper chamber at its upper end, said stopper having a lateral opening to deliver through the 50 lateral pouring aperture of the bottle neck.

10. In a non-refillable bottle, a stopper having a chamber extending through the stopper from its upper to its lower end, said chamber being restricted at its lower 55 end to provide a valve seat, a buoyant valve in said chamber and conforming closely in cross section to said chamber, said stopper having longitudinal grooves merging with said chamber to provide passage ways past 60 the valve when the valve is unseated, and means continuously tending to hold said valve seated.

In testimony whereof I affix my signature in presence of two witnesses.

GEORGE FUSSELL.
